CABINET

Herbert E. Spencer, 3852 Division Ave. SE.,
Grand Rapids, Mich. 49508

Filed Sept. 28, 1967, Ser. No. 8,772

Term of patent 14 years

(Cl. D33—19)

FIG. 1.

FIG. 2.

FIG. 3.

FIG. 4.

FIG. 1 is a perspective view of the cabinet;
FIG. 2 is a side-elevation thereof;

FIG. 3 is a front elevation thereof; and

FIG. 4 is a cross-sectional view taken along plane IV-IV of FIG. 3.

The side not shown is a mirror image of the side shown and the back of the article is plain and unornamented.

I claim:

The ornamental design for a cabinet, substantially as shown and described.
